US00D979586S

(12) United States Design Patent (10) Patent No.: US D979,586 S
Song (45) Date of Patent: * Feb. 28, 2023

(54) DISPLAY SCREEN OR PORTION THEREOF WITH A GRAPHICAL USER INTERFACE

(71) Applicant: KWAI GAMES PTE. LTD., Singapore (SG)

(72) Inventor: Congcong Song, Beijing (CN)

(73) Assignee: KWAI GAMES PTE. LTD., Singapore (SG)

() Term: 15 Years

(21) Appl. No.: 35/512,220

(22) Filed: Jul. 5, 2021

(80) Hague Agreement Data

Int. Filing Date: Jul. 5, 2021

Int. Reg. No.: DM/215339

Int. Reg. Date: Jul. 5, 2021

Int. Reg. Pub. Date: Jul. 23, 2021

(30) Foreign Application Priority Data

Jan. 22, 2021 (CN) 202130048749.4

(51) LOC (14) Cl. 14-04

(52) U.S. Cl.

USPC D14/486
